UNITED STATES PATENT OFFICE.

DANA W. WELLS, OF DANSVILLE, NEW YORK.

WATCHCASE TYPE RECEIVER.

Application filed June 25, 1925. Serial No. 39,526.

This invention relates to improvements in the construction of watch case type receivers more especially adapted for use in the reception of radio signals.

5 An object of this invention resides in providing a watch case type of receiver particularly adapted for use in radio work which is constructed in order to obtain the highest efficiency in operation and therefore greatest 10 sensitivity.

Another object of the invention resides in providing a structure which will retain the last mentioned object and which will include the usual metallic case provided with an 15 annular insulating disk in the bottom thereof provided with lateral extensions from the periphery in and against which is seated the pole pieces and substantially ring shaped magnets arranged so that the pole pieces 20 which are of angular form project radially inward from the adjacent ends of the magnet and have spaced parallel portions mounted in suitable spool ends upon which is directly wound a pair of wire coils having 25 one end of each coil electrically connected to its respective pole piece while the opposite end of each coil is electrically connected to a suitable securing means which extends through the permanent magnet and the respective pole pieces and through the case and 30 which is suitably insulated from the pole pieces and the magnet, so that when secured in rigid relation all of the parts will be mounted in assembled relation and the securing means will form a circuit for receiving the terminal connection for inserting the two coils in a suitable radio circuit for 35 operation.

The invention further comprehends improvements in the details of construction and arrangement of parts which are more particularly pointed out in the following detailed description and claims directed to a preferred form of the invention, it being understood however, that various changes in the size, formation, and arrangement of the parts may be made without departing from the spirit or scope of the invention as herein set forth.

50 In the drawing forming part of this application:—

Figure 1 is a vertical transverse sectional view through the improved receiver construction.

Fig. 2 is a bottom plan view of the magnet 55 and pole pieces with the windings thereon.

Fig. 3 is a plan view of the insulating disk member.

Fig. 4 is a side elevation of the insulating disk shown in Fig. 3.

Fig. 5 is an enlarged detail elevational view of one of the pole pieces, showing portions broken away and in section in order to illustrate the details of construction there-of.

1 indicates a metallic case which may be of the usual structure of aluminum or the like which is used in the making of the watch case type of receiver. Within the bottom portion of this case 1 is mounted 70 the annular insulating disk 2 which is provided with laterally extending projections 3 in spaced relation around the periphery thereof. This disk 2 is mounted as shown in Fig. 1 and within which is positioned the substantially ring-shaped permanent magnet 4 having the ends indicated at 5 terminating in spaced relation. Pole pieces 6 of angular form have the end portions 7 secured to the ends of the magnet 4 and positioned on the 75 under side thereof as clearly shown in Figs. 1 and 2. The other ends 8 of these pole pieces extend upwardly within the case 1 in spaced parallel relation at opposite sides of the antenna of the magnet 4 and upon which are positioned pairs of spool ends 9 at the top and bottom portions of the ends 8 of the pole pieces respectively. The spool ends at the lower end portions 8 of the pole pieces are held in position by the angularly arranged end 7 and the projection 10 extending in an opposite direction therefrom. The spool ends at the upper ends of the portions 8 are retained by the outwardly struck portions 11 from the upper edges. Between the 80 spool ends and within a predetermined zone around each pole piece is wound the wire coil 12 of suitable enameled wire directly upon the pole piece in order that a maximum number of convolutions may be wound within said predetermined zone on said pole piece. The end of each coil of wire is electrically connected to the pole piece as indicated at 13 in Fig. 5, so that the pole pieces and magnet form the electric circuit between 85 the coils.

Screws 14 are extended through the ends of the magnet 4, the pole pieces 7 are suit-

ably insulated therefrom by the sleeve 15 and then extended through the disk 2 and the case 1 and upon the back of the case receives the nut 16 so that the parts may be suitably and rigidly mounted in assembled relation within the case. The ends of the coils are connected to the lugs 17 which are secured on top of the insulating washers 18 and fit under the head of the screws 14 to provide convenient means for connecting the coils 12 in circuit.

The direct mounting of the coils 12 on the pole pieces 8 provides for the reception of a greater number of turns of wire within a predetermined zone on said pole pieces so that greater efficiency can be obtained as a result of this construction over the usual present construction of receivers in which the pole pieces are first provided with an insulating covering of suitable form before the wire is wound thereon. In addition, the electrical connection of the ends of the coils 12 as indicated at 13 to the pole pieces, utilizes the pole pieces and the magnet 4 for forming the circuit connection between the coils 12 which also forms a magnetic circuit of the receiver. The provision in the insulating disk 2 between the magnet and the pole pieces and the case for insulating the magnet spool pieces from the case is an additional feature of the present construction as it entirely eliminates any electrical connection of the circuit with the coils 12 or with the case which is now present in the ordinary type of receiver used through the direct contact of the magnet and pole pieces with the metallic case.

In watch case receivers of the ordinary type as now used as above set forth, should the insulation become destroyed on one of the wires the same contacts with the pole piece on the magnet, the circuit is made with the case and the efficiency of the operation of the receiver lessened by reason of the leakage in the current to the case. In the present construction the insulating sleeve 15 and the insulating washers 19 prevent electrical

connection of the screws 14 with the case so that no electrical connection is in any way made with the receiver case.

This construction has been found to be highly efficient in operation and exceedingly sensitive due to the advantages obtained as above described.

What is claimed is:—

A watch case type radio receiver, comprising a metallic case, a substantially ring-shaped magnet having the ends terminating in predetermined space relation, said magnet fitting within said case, a pair of pole pieces of angular form having one end of each secured to the end portion of the magnet and extending radially inward, the opposite ends being arranged in spaced parallel relation in the central portion of the magnet, spool end disks mounted on the pole pieces at opposite ends of the parallel portions, said pole pieces being formed with struck out portions for retaining the end disk in position, a maximum number of wire coil convolutions mounted directly on each pole piece between the end disks and within a predetermined zone around said pole pieces, one end of each wire being electrically connected with the pole piece, an annular disk of insulating material forming with lateral projecting portions at spaced intervals on the periphery mounted in the bottom of the metallic case and insulating the pole pieces and magnet from the case, and assembling means insulated from the case extending through the ends of the magnet, the pole pieces, insulating disk and the case for rigidly mounting the several parts together, said means being insulated from the magnet and pole pieces, the ends of the coils being electrically connected thereto and the pole pieces and magnet providing both the magnetic circuit and the electrical circuit between the wire coils on each pole piece.

In testimony whereof I affix my signature.

DANA W. WELLS.
